TOY MOTOR KIT

John W. Reed, St. Petersburg, Fla.

Application February 21, 1956, Serial No. 566,953

3 Claims. (Cl. 310—1)

This invention relates to a toy or educational or amusement device, and more particularly to a toy electrical motor which is adapted to be assembled by children or other persons.

The object of the invention is to provide a toy electric motor which can be readily assembled by children or other persons to thereby provide amusement and recreation as well as education and instruction to the children or other users.

Another object of the invention is to provide a toy electric motor which is adapted to be furnished in knock-down condition so that it can be readily assembled by children or the like, the present invention including a number of parts which are adapted to be detachably mounted in place and whereby numerals are provided between or adjacent to the coils of the motor so as to indicate exactly where certain of the electric wires are to be connected.

A further object of the invention is to provide a toy electric motor in the form of a do-it-yourself kit which is extremely simple and inexpensive to manufacture.

Other objects and advantages will be apparent during the course of the following description.

In the accompanying drawings, forming a part of this application, and in which like numerals are used to designate like parts throughout the same.

Figure 1 is an end elevational view of the toy electric motor, constructed according to the present invention.

Figure 2 is a side elevational view of the motor.

Figure 3 is a top plan view of the motor.

Figure 4 is a bottom plan view of the motor.

Figure 5 is a sectional view taken on the line 5—5 of Figure 2.

Figure 6 is a sectional view taken on the line 6—6 of Figure 2.

Figure 7 is a fragmentary elevational view illustrating the discs with the numerals and contacts thereon.

Figure 8 is a fragmentary sectional view illustrating the wiper elements and contacts.

Figure 9 is a view illustrating one of the coils.

Figure 10 is a fragmentary sectional view illustrating the wiper elements.

Referring in detail to the drawings, the numeral 10 designates a horizontally disposed rectangular base or platform which can be made of any suitable material such as metal, and the base 10 is provided with a plurality of downwardly extending vertically disposed flanges 11, Figure 4. Arranged in the base 10 intermediate the ends thereof is a transversely disposed cutout or slot 12, and extending beneath the slot or cutout 12 is an insulated strip 13, Figure 2. Suitable securing elements such as rivets 14 serve to secure the strip 13 to the base 10.

Detachably connected to the strip 13 is a bracket 15 which includes a horizontally disposed lower flange 16 which is secured to the strip 13 in any suitable manner, as for example by means of bolt and nut assemblies 18. The bracket 15 further includes a vertically disposed member 17 for a purpose to be later described.

2

There is further provided a pair of L-shaped lugs 19 which are secured to the upper surface of the base 10, and a vertically disposed insulated arm 20 extends upwardly from one of the lugs 19 and is secured thereto. A metal contact finger 21 is pivotally connected to each of the insulated arms 20, and each of the fingers 21 is provided with a finger engaging portion 22 whereby the members 21 can be moved into and out of electrical engagement with the ends of a pair of batteries 23. For retaining the batteries 23 in place, a support member 24 is provided, and the support member 24 includes a pair of arcuate sections 25 which are interconnected together by a web 26, the arcuate sections 25 engaging the pair of batteries 23. The ends of the support member 24 terminate in a pair of flat ears or flanges 27 which are secured to the base 10 in any suitable manner, as for example by means of the securing elements 28, Figure 3.

Extending upwardly from the base 10 and formed integral therewith or secured thereto is a vertically disposed plate 29 which has an insulated bar or strip 30 secured thereto, and a metal spring clip 31 is secured to the bar 30. The spring clip 31 electrically connects adjacent ends of the batteries 23 together.

There is further provided a second bracket which is indicated generally by the numeral 32, and the bracket 32 includes a lower horizontally disposed flange 33 and a vertically disposed member 34. A shaft 35 is rotatably supported by bearings mounted in the members 17 and 34 of the brackets 15 and 32, Figure 2, and the shaft 35 is provided with an intermediate enlarged portion 36 which is interposed between the pair of bearings in the members 17 and 34. The bracket 32 may be secured to the base 10 by means of bolt and nut assemblies 37.

Extending transversely across the top of the base 10 is a metal strip 38, and a metal ring member 40 may be secured to the strip 38 through the medium of a bolt and nut assembly 43. The strip 38 may be secured in place to the base by means of bolt and nut assemblies 39. Extending inwardly from the ring member 40 is a plurality of coils 41, and the coils 41 may be secured to the ring member 40 through the medium of bolt and nut assemblies 42. Suitable numerals such as the numerals indicated by the reference character 44, Figure 2, are arranged on the ring member 40 contiguous to the coils 41.

Secured to the outer surface of the bearing 34 of the bracket 32 is a circular disc 45 of insulated material, and connected to the disc 45 is a plurality of contacts 46, the contacts 46 being equal in number to the coils 41. Terminals 47 are electrically connected to the contacts 46, and the terminals 47 project through the disc 45 and through the member 34. Wires 48 serve to electrically connect the terminals 47 to the coils 41. Numerals such as the numeral 53, Figure 7, are arranged contiguous to the contacts 46 so as to insure that the proper contacts 46 will be electrically connected to the proper coils 41.

Extending outwardly from the shaft 35 and secured thereto is a transversely disposed armature 49 of magnetic material which is adapted to rotate within the orbit of the ring member 40. Mounted on the shaft 35 is a disc or plate 50 which is made of metal, and the plate 50 is provided with a pair of diametrically opposed wiper elements 51 which slidably engage the terminals 47.

From the foregoing, it is apparent that there has been provided a toy electric motor which is adapted to be assembled by children or other persons so as to provide a source of recreation and amusement. The parts are adapted to be sold as a knock-down do-it-yourself kit and suitable instructions may be furnished so as to insure the ready assembly of the motor. It is to be noted that the various parts are secured in place by bolt and nut assemblies which can be readily removed or replaced when desired and the assembly can be completed without

requiring any special tools except, perhaps, a screwdriver or a pair of pliers or wrench. When the parts are properly assembled, the fingers 21 can be moved to the position shown in Figure 3 whereby electrical current from the batteries 23 will be supplied from the batteries 23 through a wire 52 and this current will flow through the bracket 15. The current continues to flow from the bracket 15 to the shaft 35 and armature 49. The coils 41 are selectively energized so as to set up a field of magnetic attraction to thereby cause rotation of the armature 49 and since the armature 49 is secured to the shaft 35, then the shaft 35 will rotate. It is to be noted that the plate 50 includes a pair of diametrically opposed wiper elements 51 which engage the terminals 47 as the shaft rotates to thereby selectively make and break the circuit to the various coils 41 as the shaft rotates so that as long as the circuit is completed from the batteries 23, the shaft 35 and armature 49 will continue to rotate. With the armature 49 and shaft 35 rotating, the child or other person will derive much pleasure and amusement from the toy electric motor.

It is to be noted that the disc 45 includes the plurality of contacts 46 which are equal in number to the coils 41, and the contacts 46 have the numerals 53 arranged contiguous thereto. The numerals 53 correspond to the numerals 44 on the outer surface of the ring member 40 and when the motor is being assembled or put together, the wires 48 lead from coils 41 to contacts 46 and the wires 48 connect coils 41 to contacts 46 of the same numeral. As the shaft 35 rotates, the diametrically opposed wiper elements 51 move into and out of engagement with the terminals 47 which lead from the contacts 46 so as to selectively open and close the circuits to the coils 41. When the device is not being used, the fingers 21 can be moved up manually by gripping the portions 22 to thereby open the circuit to the motor so that the batteries 23 will not be run down or used needlessly. In most of the figures of the drawings, the wires leading between the various parts have been omitted in order to clarify the construction of the parts but in Figure 5 the various wires are illustrated. As shown in Figure 9, a yoke or clip 54 may be connected to one of the wires 48 which lead to each coil 41, and the clips 54 are adapted to be arranged in engagement with the bolts 42 in order to properly assemble the device.

The motor of the present invention operates on a magnetic principle and when the circuit from the battery is completed, the coils 41 are energized in turn as the wiper element 51 rotates around the terminals 47. The present invention is adapted to be sold as an assemble it yourself item that may be put together readily by children over the age of six.

I claim:

1. A toy electric motor comprising a horizontally disposed rectangular base provided with a transversely disposed intermediate rectangular cutout, a plurality of vertically disposed flanges depending from the outer edges of said base, an insulated strip extending beneath said cutout and secured to said base, a first bracket including a vertically disposed member provided with an aperture and said bracket further including a horizontally disposed flange detachably connected to said strip, a pair of batteries supported on said base, a support member including a pair of arcuate superposed sections engaging said batteries and said support member including apertured ears secured to said base, a pair of L-shaped lugs secured to said base, an insulated arm extending upwardly from one of said lugs and secured thereto, a metal contact finger pivotally connected to said arm, a metal contact finger pivotally connected to the other lug, said fingers being mounted for movement into and out of engagement with said batteries, a vertically disposed plate extending upwardly from said base adjacent the rear of said cutout, an insulated bar secured to said plate, a curved spring clip secured to said bar and interconnecting the adjacent ends of said batteries together, a first wire leading from one of said fingers to said bracket, a second bracket including a horizontally disposed flange secured to an end of said base, said second bracket further including a vertically disposed member extending upwardly from said last named flange and provided with an aperture therein, an insulated plate provided with an aperture therein secured to the outer surface of the vertically disposed member of said second bracket, a horizontally disposed rotatable shaft extending through the apertures in the aperture in the vertically disposed member of said first bracket and the aperture in the insulated plate secured to the vertically disposed member of said second bracket, said shaft including an enlarged intermediate portion interposed between said members, an armature extending transversely from said shaft and secured thereto, a metal strip secured to the upper surface of said base and extending transversely there across, a vertically disposed ring member extending upwardly from said strip and secured thereto, a plurality of coils extending inwardly into said ring member and secured thereto, an insulated disc secured to the outer surface of said second bracket, a plurality of contacts extending outwardly from said disc, terminals connected to said contacts and projecting

ends of said batteries together, a first wire leading from one of said fingers to said bracket, a second bracket including a horizontally disposed flange secured to an end of said base, said second bracket further including a vertically disposed member extending upwardly from said last named flange and provided with an aperture therein, an insulated plate provided with an aperture therein secured to the outer surface of the vertically disposed member of said second bracket, a horizontally disposed rotatable shaft extending through the apertures in the aperture in the vertically disposed member of said first bracket and the aperture in the insulated plate secured to the vertically disposed member of said second bracket, said shaft including an enlarged intermediate portion interposed between said members, an armature extending transversely from said shaft and secured thereto, a metal strip secured to the upper surface of said base and extending transversely there across, a vertically disposed ring member extending upwardly from said strip and secured thereto, a plurality of coils extending inwardly into said ring member and secured thereto, an insulated disc secured to the outer surface of said second bracket, a plurality of contacts extending outwardly from said disc, terminals connected to said contacts and projecting

2. A toy electric motor comprising a horizontally disposed rectangular base provided with a transversely disposed intermediate rectangular cutout, a plurality of vertically disposed flanges depending from the outer edges of said base, an insulated strip extending beneath said cutout and secured to said base, a first bracket including a vertically disposed member provided with an aperture and said bracket further including a horizontally disposed flange detachably connected to said strip, a pair of batteries supported on said base, a support member including a pair of arcuate superposed sections engaging said batteries and said support member including apertured ears secured to said base, a pair of L-shaped lugs secured to said base, an insulated arm extending upwardly from one of said lugs and secured thereto, a metal contact finger pivotally connected to said arm, a metal contact finger pivotally connected to the other lug, said fingers being mounted for movement into and out of engagement with said batteries, a vertically disposed plate extending upwardly from said base adjacent the rear of said cutout, an insulated bar secured to said plate, a curved spring clip secured to said bar and interconnecting the adjacent ends of said batteries together, a first wire leading from one of said fingers to said bracket, a second bracket including a horizontally disposed flange secured to an end of said base, said second bracket further including a vertically disposed member extending upwardly from said last named flange and provided with an aperture therein, an insulated plate provided with an aperture therein secured to the outer surface of the vertically disposed member of said second bracket, a horizontally disposed rotatable shaft extending through the apertures in the aperture in the vertically disposed member of said first bracket and the aperture in the insulated plate secured to the vertically disposed member of said second bracket, said shaft including an enlarged intermediate portion interposed between said members, an armature extending transversely from said shaft and secured thereto, a metal strip secured to the upper surface of said base and extending transversely there across, a vertically disposed ring member extending upwardly from said strip and secured thereto, a plurality of coils extending inwardly into said ring member and secured thereto, an insulated disc secured to the outer surface of said second bracket, a plurality of contacts extending outwardly from said disc, terminals connected to said contacts and projecting

through said second bracket, wires leading from said coils to said contacts, and a plate mounted on said shaft and including a pair of diametrically opposed wiper elements mounted for movement into and out of engagement with said terminals, there being numerals on the outer surface of said ring member contiguous to said coils, the contacts being equal in number to the number of coils, there being numerals on said disc adjacent said contacts.

3. A toy electric motor comprising a horizontally disposed rectangular base provided with a transversely disposed intermediate rectangular cutout, a plurality of vertically disposed flanges depending from the outer edges of said base, an insulated strip extending beneath said cutout and secured to said base, a first bracket including a vertically disposed member provided with an aperture and said bracket further including a horizontally disposed flange detachably connected said strip, a pair of batteries supported on said base, a support member including a pair of arcuate superposed sections engaging said batteries and said support member including apertured ears secured to said base, a pair of L-shaped lugs secured to said base, an insulated arm extending upwardly from one of said lugs and secured thereto, a metal contact finger pivotally connected to said arm, a metal contact finger pivotally connected to the other lug, said fingers being mounted for movement into and out of engagement with said batteries, a vertically disposed plate extending upwardly from said base adjacent the rear of said cutout, an insulated bar secured to said plate, a curved spring clip secured to said bar and interconnecting the adjacent ends of said batteries together, a first wire leading from one of said fingers to said bracket, a second bracket including a horizontally disposed flange secured to an end of said base, said second bracket further including a vertically disposed member extending upwardly from said last named flange and provided with an aperture therein, an insulated plate provided with an aperture therein secured to the outer surface of the vertically disposed member of said second bracket, a horizontally disposed rotatable shaft ex-
